UNITED STATES PATENT OFFICE.

JOHN P. WHITMORE, OF SAN MARINO, CALIFORNIA, ASSIGNOR TO COLUMBIA MILLS INCORPORATED, OF NEW YORK, N. Y., A CORPORATION OF NEW YORK.

WINDOW BLIND.

Application filed November 11, 1926. Serial No. 147,740.

This invention relates to blinds for controlling the admission of light through windows, doors, and the like, and particularly to blinds of the type known as Venetian blinds. The principal object of the invention is to provide a Venetian blind which will admit a maximum amount of light to a room while at the same time minimizing the glare upon the eyes of persons in the room.

10 Blinds of the type known as Venetian blinds comprise, in general, a plurality of flat strips extending transversely of the window or other opening, and disposed one above the other so as to provide spaces therebetween, and means for tilting said slats in either direction from the horizontal so as to control the admission of light through said spaces. Such slats may therefore be tilted into such a position as to reflect exterior light from the upper surfaces thereof into the room to light the same while wholly preventing or reducing to a minimum the direct passage of light rays between the slats into certain portions of the room, for example, 20 the lower portion thereof. This is of material advantage, for example, in office rooms and the like where persons are normally engaged within said room and particularly in the lower portion thereof, since it provides ample light within the room without causing the light rays to reach the eyes of such persons directly. A particular object of my invention is to increase the reflection of light from the upper surfaces of the slats and thus 30 provide an increased amount of indirect lighting while at the same time reducing or maintaining at a minimum the reflection of light from the surfaces of the slats which are normally disposed inwardly toward the room under such conditions.

The above objects are accomplished according to my invention by providing each of said slats of the Venetian blind with a light reflecting upper surface having a metallic luster and a light absorbing lower surface capable of reflecting materially less light than the upper surface. Different means may be employed for providing the slats with the above described surfaces and 40 I will now describe certain specific constructions embodying my invention.

The accompanying drawings illustrate certain embodiments of my invention, and referring thereto:

Fig. 1 is an inside elevation of a Venetian blind embodying my invention.

Fig. 2 is a vertical section thereof on line 2—2 in Fig. 1.

Fig. 3 is an enlarged vertical section of one of the slats of said Venetian blind.

Fig. 4 is a partial vertical section on line 4—4 in Fig. 1 but with the slats tilted to a different position.

Fig. 5 is a view similar to Fig. 3, showing a modified form of slat.

The Venetian blind is shown as mounted within a frame comprising vertical side members 1 and horizontal top and bottom members 2 and 3. Said frame may be the frame of a window, door or any other opening in a wall, but for the purpose of illustration it may be considered as being a frame of a window in an exterior wall of a room. An upper supporting plate or sill 4 is secured in position beneath the top frame member 2 and may be provided with a groove 5 extending longitudinally thereof and with pulleys 6, 7 and 8 rotatably mounted on shafts 9 therein.

A top slat 10 may be provided at its ends with projecting pins 11 which may be rotatably mounted in brackets 12 depending from the sill 4. Two fabric supporting strips 13 may be secured at their upper ends to the supporting slat 10 so as to constitute loops extending downwardly to the bottom of the space to be occupied by the blind. In the bottom of the loop so formed a bottom slat 14 may be secured in any suitable manner. A plurality of transverse supporting strips 16 of suitable fabric extend across between the opposite sides of strips 13 at positions equally spaced throughout the height thereof and the transverse slats 17 rest upon said transverse strips 16 and between the opposite sides of strips 13 and extend transversely substantially across the entire width of the opening between the side members 1.

Lifting cords 20 are secured in any suitable manner to the bottom slat 14 and pass upwardly through slots 22 in the slats 17 and through slots 23 in the top slat 10 and over pulleys 6 and 7, thence through groove 5 and over pulley 8, and thence downwardly into position adjacent one of the side members 1, said cords being advantageously joined together at their ends or being formed as a single cord so as to provide a loop at this

position. Suitable means such as headed stud 24 may be provided so that the ends of said cords may be secured thereto so as to hold the bottom slat 14 in any position to 5 which it may be raised, as is customary in such devices.

In order to provide for tilting the slats of the blind, a cord 27 may be secured at one end to the top of the upper slat 10 as indicated at 28 and may extend around behind and beneath said slat as indicated at 29, passing over pulley 30 on bracket 12 and downwardly alongside one of the side members 1 to form a loop 31, thence upwardly 10 in front of the upper slat 10 and around above and behind the same as indicated at 32, and may be secured at its other end to the bottom of said slat 10 as shown at 33. It may be seen that with such an arrangement 15 pulling of the cord at one side of loop 31 will cause the slats to be tilted in one direction while pulling at the other side of said loop will cause the slats to be tilted in the reverse direction.

25 The upper slat 10 may be provided with a spring catch 35 adapted to engage in any one of a plurality of notches 36 in bracket 12 so as to hold said slat, together with the slats 17, in any one of a plurality of different positions to which they may be tilted by the tilting means above described.

The above described parts of the blind are all well-known in practice and form no essential part of my invention, but have 35 been described in some detail in order that a clear understanding may be had of the advantages of such invention. According to this invention each of the slats 17 (and also if desired the upper slat 10 and bottom 40 slat 14) is provided with an upper light reflecting surface 40 having a metallic luster and a consequently high capacity for light reflection and a light absorbing lower surface 41 capable of reflecting materially less 45 light than said upper surface. One means of forming such surfaces is illustrated particularly in Fig. 3 in which the slat 17 is shown as a strip of wood or metal, the upper surface of which is coated with a light reflecting coating 40 consisting, for example, of metallic paint such as aluminum or 50 bronze paint, and its lower surface coated with a light absorbing material, such as a non-metallic paint. The aluminum paint 55 which may advantageously be used for coating the upper surface of the slats consists of aluminum powder in a body of lacquer or varnish or other suitable material.

Under normal conditions, with fairly 60 strong light outside, the blind may advantageously be adjusted to a position in which the slats are inclined outwardly and downwardly for example, to the position shown in Fig. 2. With the slats in such position 65 a relatively small amount of light is per-

mitted to pass directly through the spaces 15 between the slats, and in fact the direct passage of light through such spaces to the eyes of the persons in the lower portion of the room and below the level of the major 70 portion of the blind is substantially entirely prevented. Light rays indicated at *a*, however, strike the upper surfaces of the slats and are effectively reflected therefrom as indicated at *b* so as to strike the ceiling or 75 the opposite wall of the room and thus light the same indirectly. Light rays such as indicated at *a'* however, upon being reflected as at *b'*, strike the lower surfaces of the slats and are largely absorbed thereby so that there 80 is a minimum amount of light reflected from the lower surfaces of the slats to the eyes of persons in the room. It is possible, therefore, with such a construction, to look directly at the blind without obtaining any 85 effect of glare, as all that is seen is the light absorbing lower surfaces of the slats, while at the same time the room is well lighted by means of the light rays reflected 90 from the upper surfaces of the slats. 90

It will be understood of course, that the Venetian blind above described may be adjusted to any other desired position. For example, when the exterior light is dim as in case of cloudy weather the slats may be 95 inclined downwardly and inwardly as shown in Fig. 4 so as to permit a greater proportion of the light rays from the exterior to pass directly through the spaces 15 between the slats as indicated at *c*. When the slats are in this position they also serve 100 to reflect light from the exterior into the room, while at the same time no objectionable glare is produced, since the persons in the room are in general somewhat below the level of the major portion of the blind and hence would see only the edges or the lower 105 surfaces of most of the slats, while even if the upper surfaces of such slats were visible from certain portions of the room, there 110 would be but little reflection therefrom owing to the dimness of the exterior light. 110

Other means may be employed for providing the light reflecting and light absorbing surfaces of the slats. For example, as 115 shown in Fig. 5 each of the slats 17 may constitute a flat strip of metal whose upper surface 40' may be polished or otherwise treated so as to give it a high metallic luster and a consequently high reflecting power, while a coating 41 of suitable light absorbing material such as non-metallic paint may be applied to the lower surface 120 thereof. 120

I claim:

1. In a Venetian blind, a slat provided with an upper surface having a metallic luster and a lower surface of light absorbing material. 125
2. In a Venetian blind, a slat provided 130

with a light reflecting upper surface having a metallic luster and a light absorbing lower surface capable of reflecting materially less light than said upper surface.

3. In a Venetian blind, a slat comprising a flat strip having a light reflecting coating of metallic paint on its upper surface and

a light absorbing coating of non-metallic paint on its lower surface.

In testimony whereof I have hereunto ¹⁰ subscribed my name this 3 day of November, 1926.

JOHN P. WHITMORE.
